AUDIO FREQUENCY REGENERATOR IN A MUSICAL INSTRUMENT

Original Filed Aug. 8, 1929

FIG. 1

FIG. 2

INVENTOR.

John Hays Hammond, Jr.
BY Albert M. Austin
ATTORNEY.

UNITED STATES PATENT OFFICE

2,038,995

AUDIO FREQUENCY REGENERATOR IN A MUSICAL INSTRUMENT

John Hays Hammond, Jr., Gloucester, Mass.

Application August 8, 1929, Serial No. 384,284
Renewed February 6, 1931

4 Claims. (Cl. 250—20)

This invention relates to musical instruments, and more particularly to a musical instrument having a vibratable element, and to mechanism for amplifying the vibrations of said element at 5 the will of the operator.

According to a preferred form of the invention a piano is provided having a loud speaker mounted adjacent the vibratable elements thereof. A radio receiver may be incorporated in the piano 10 utilizing the loud speaker for radio reception purposes. When using the combined piano and radio receiver for radio reception, the piano may be used as a mechanical filter for eliminating undesirable sounds, such as static. When using the 15 piano as a mechanical filter, the energy delivered to the vibratable elements of the piano by the loud speaker is picked up by suitable pick-up devices and fed back into the input of the audio amplifier of the radio receiver.

20 If desired, the combined piano and radio receiver may also be used as a regenerative piano, in which case the energy delivered to the vibratable element of the piano by the loud speaker is picked up by suitable pick-up devices and fed 25 back into the audio amplifier of the radio receiver, thus decreasing the damping when the piano is being played by an artist in the ordinary manner.

The invention also consists in certain new and original features of construction and combinations of parts hereinafter set forth and claimed.

30 Although the novel features which are believed to be characteristic of this invention will be particularly pointed out in the claims appended hereto, the invention itself, as to its objects and advantages, the mode of its operation and the manner of its organization may be better understood by referring to the following description taken 35 in connection with the accompanying drawing forming a part thereof, in which

40 Fig. 1 is a side elevation partly in section of a piano with a diagrammatic showing of the amplifying means in accordance with the present invention; and

45 Fig. 2 is a broken sectional front view showing a modified form of pick-up means.

Like reference characters denote like parts in the several figures of the drawing.

In the following description and in the claims 50 parts will be identified by specific names for convenience, but they are intended to be as generic in their application to similar parts as the art will permit.

55 Referring to the drawing more in detail, the invention is shown by way of illustration as applied to a grand piano 10 having strings 11 and

a sounding board 12. Loud pedal 13 is employed for controlling the amplitude of vibrations of the strings in a well known manner.

Located at various points on the sounding board 12 are a plurality of pickup devices illustrated somewhat diagrammatically by 14 which are adapted to be actuated by the vibrations of said sounding board and to produce a varying electric current which is applied to transformers 15, the secondaries of which are connected to 10 a plurality of potentiometers 16. Pick-up devices 14 may, for example, be the type disclosed in P. R. Fortin Patent No. 1,689,524, issued October 30, 1928. Said potentiometers are connected in series to a potentiometer 17, the movable contact 15 18 of which is mounted on a lever 19 which is actuated from loud pedal 13 by a rod 20. Said rod carries a collar 22 which cooperates with lever 19 for elevating the same when pedal 13 is depressed. Spring 21 may be employed for 20 normally holding lever 19 in its lower position.

Radio receiver 25 which may be of any well known type as for example, including a radio frequency amplifier 26, a detector section 27, and an audio frequency amplifier 28 may be connected to an antenna 29 through knife switch 30. The output circuit of receiver 25 may be connected to loud speaker 31 by leads 32.

A loud speaker illustrated somewhat diagrammatically by 31 is preferably mounted on or adjacent sounding board 12 and the dead weight of said speaker is taken up by spring 33 which is carried on frame 34 forming a part of the piano. The speaker 31 may, for example, be of the type illustrated in Fig. 2 of applicant's Patent No. 1,893,892, issued January 10, 1933. The variable contact 18 and one side of potentiometer 17 are connected through switch 23 across the input circuit of detector section 27 whereby the audio frequency currents produced by pickup devices 14 40 may be applied to said detector element, amplified in audio amplifier 28 and used to actuate loud speaker 31.

Pickup devices 14 are preferably located at anti-nodal areas on sounding board 12 so that a maximum response will be obtained. Loud speaker 31 is preferably located at a nodal point on said sounding board so that the operation of the sounding board will not be interfered with thereby.

The position of the nodal and anti-nodal points 50 in a piano sounding board may be determined by sprinkling sand on the board and noting the distribution thereof. Areas where the sand collects are nodal areas. Areas free from sand are the anti-nodal areas.

Usually there is some part, as for instance, near the corner of the sounding board, which is comparatively dead for all notes of the piano. This would constitute a nodal point for the loud speaker.

Although the anti-nodal points will change with different notes, it has been found that there are certain anti-nodal areas for certain groups of notes. For instance, the bass notes will have one general anti-nodal area, the intermediate notes will have another and the high treble notes will have another. By using a plurality of pick-up devices 14 and locating one at each anti-nodal area, good pick-up is obtained no matter which note of the entire piano scale is struck.

In the operation of the above described system as a radio receiver, switch 30 is closed and the signals are received in receiver 25, amplified at radio frequency in section 26, detected in section 27, amplified at audio frequency in section 28 and applied to loud speaker 31. The reaction of loud speaker 31, both mechanically and through the compressional waves generated thereby, causes vibrations of strings 11 and sounding board 12. These vibrations are then picked up by pickup devices 14 and used to generate currents which are then applied to detector section 21 and amplified in audio frequency amplifier 28 and again applied to the loud speaker.

A system of audio frequency regeneration is accordingly provided in which the tones produced by loud speaker 31 are determined by the qualities of the sounding board 12. Furthermore the pick-up from the various portions of the sounding board may be independently controlled by the operation of potentiometers 16 and the amount of regeneration may be controlled by potentiometer 17 which governs the amount of energy applied to the input circuit of detector section 27.

In operating the system as a piano, switch 30 is open and the piano is actuated in the usual manner. Vibrations of strings 11 then cause vibrations of sounding board 12 which are picked up by pickup device 14, passed through the detector and audio amplifier of receiver 25 and applied to loud speaker 31 in the manner pointed out above. An audio frequency regeneration is thus obtained which is controlled by the potentiometers 16 and 17. It has been found that when loud pedal 13 is depressed, thereby raising the dampers from the strings 11, there is a tendency for excessive regeneration which would distort the output of the loud speaker. This is prevented by so connecting potentiometer 17 across the input circuit of the detector that when loud pedal 13 is depressed the power applied to the detector is decreased. It is obvious that any desired adjustment may be made to secure the proper operating characteristics.

A modified form of pickup device is shown in Fig. 2 in which pickup devices illustrated somewhat diagrammatically by 38 are located adjacent strings 11 and are actuated by the vibrations of said strings. A plurality of said pickup devices are shown mounted adjacent various groups of strings. It is understood that they would be so constructed as to secure a maximum response to the frequencies of the strings with which they are associated. Such pick-ups may, for example, be of the construction shown in Figs. 1, 2 and 3 of applicant's Patent No. 1,893,892, referred to above. Pickup devices 38 are connected to transformers 15, the secondaries of which are applied to potentiometers 16 in the manner shown in Fig. 1.

Although a plurality of pickup devices have

been shown for both the sounding board and the strings, it is obvious that a single pickup device can be employed if desired.

It is to be noted that the tonal qualities of the sounding board are utilized in controlling the tonal qualities of the music produced by the loud speaker 31. In fact the sounding board may be considered to operate as a filter for removing undesired tones from the system. At any rate the quality of the tones produced by loud speaker 31 is improved and the volume thereof is amplified by the above described system. It is obvious that the system may be applied to any well known type of radio receiver possessing means for amplifying currents at audio frequency.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. A system for improving the characteristics of received radio selections, comprising a radio receiver having an audio frequency amplifier stage, a musical instrument having a sounding board, a loud speaker, means mounting said loudspeaker in vibrational coupling with said sounding board, means actuating said loud speaker by oscillatory energy from said amplifier stage, a pick-up device connected to receive vibratory energy from said sounding board and to translate the same into electrical energy, and a circuit adapted to apply said electrical energy from said pick-up device to the in-put circuit of said amplifier stage, whereby the vibrations of said sounding board caused by received radio selections are again transmitted through said amplifier stage, amplified therein and are again applied to the loud speaker.

2. A system for improving the characteristics of received radio selections comprising a radio receiver having an audio frequency amplifier stage, a musical instrument having a sounding board, a loud speaker, means mounting said loud speaker in vibrational coupling with said sounding board, means actuating said loud speaker by oscillatory energy from said amplifier stage, a plurality of pick-up devices connected to receive vibratory energy from said sounding board and to translate the same into electrical energy and a circuit adapted to apply said electrical energy from said pick-up devices to the in-put circuit of said amplifier stage, whereby the vibrations of said sounding board caused by received radio selections are again transmitted through said amplifier stage, amplified therein and are again applied to the loud speaker.

3. In a tonal system comprising a radio receiver having an audio frequency amplifier stage, a piano having a sounding board and a loud pedal, a loud speaker, means mounting said loud speaker in vibrational coupling with said sounding board, means actuating said speaker by energy from said amplifier stage, a plurality of pick-up devices connected to receive vibrational energy from said sounding board and to translate the same into electrical energy, a circuit adapted to apply said electrical energy from said pick-up devices to the input circuit of said amplifier stage whereby the vibrations of said sounding board are transmitted through said amplifier, amplified therein and are again applied to the loud speaker, means

for individually controlling the response of said devices and means in the input circuit of said amplifier and connected to the loud pedal of said piano for decreasing the amount of energy applied to said amplifier stage when the loud pedal is depressed.

4. In a radio receiving system, means for receiving radio signals, an audio frequency amplifier stage fed thereby, a piano having a sounding board, a sound propagating element actuated by

said amplifier stage and in vibrational coupling with said sounding board, a pick-up device connected to receive vibrational energy from said sounding board and to translate the same to electrical energy and a circuit connecting said pick-up device to the input of said amplifier stage whereby received sound energy passes regeneratively through said amplifier. 5
